UNITED STATES PATENT OFFICE.

RAFAEL RAMOS AND AMBROSE DE CÁRDENAS, OF COLONIA "LA CAOBA," AGUADA DE PASAJEROS, SANTA CLARA, CUBA.

PLOWING-MACHINE.

1,367,755.

Specification of Letters Patent.

Patented Feb. 8, 1921.

Application filed February 5, 1919. Serial No. 275,237.

To all whom it may concern:

Be it known that we, RAFAEL RAMOS and AMBROSE DE CÁRDENAS, citizens of the Republic of Cuba and of the United States of America, respectively, residing at Colonia "La Caoba," municipal district of Aguada de Pasajeros, Province of Santa Clara, Republic of Cuba, have invented a new and useful Plowing-Machine, of which the following is a specification.

This invention relates to plowing machines, and its object is to provide certain improvements in the construction thereof so as to give the plows an efficient resistance to dig into the ground by a secure connection with the machine frame, instead of being carried behind same without pressure as it happens now in the plowing tractors at present in use.

Another object of this invention is to provide means for cutting the earth in front of the plows, thus aiding the subsequent work of the plows, and which also serve as gyroscopic supports for the plows.

A further object of the invention is to provide means for adjusting the depth at which the earth cutting means and the plows are to work, and also for raising them at the same time when any obstruction is found on the ground.

And still a further object of the invention is to provide means for raising and lowering at will the plows independently from the earth cutting means, every time that it is required to clean off the earth deposited thereon and when it may be desired to replace any piece thereof.

The invention is described with reference to the figures of the annexed drawings, in which:

Figure 1 is a side elevation of a plowing machine provided with the improvements which form the subject-matter of this invention.

Fig. 2 is an upper plan view thereof, partially in section.

Fig. 3 is a front elevation of the machine, partially in section.

Fig. 4 is a rear elevation of the machine.

Fig. 5 is an enlarged detail in elevation of the front set of supporting wheels of the machine.

This machine comprises a chassis 1 mounted on a pair of tread wheels 2 located at the rear part of the machine and secured

upon a shaft 3 gyroscopically supported on bearings 4 fixed by means of screws beneath the sides of chassis 1, and on a pair of steering wheels 5 located at the front part of the machine and gyroscopically mounted on 60 trunnions 6 projecting laterally from double-square shape supporting pieces 7 provided with a vertical pivot 8 upon which is rotatorily mounted a sleeve 9 formed at each end of a horizontal cross-bar 10 upwardly provided at its central portion with an extension formed by two parallel lugs, a front one 11 and a rear one 12 leaving between them a cavity 13 of concave-arched bottom 13' wherein is lodged the pending 70 central portion 14 of a cross-bar 15 secured by its squarely bent ends and by means of screws upon the inner face of the sides of frame 1, the central pending portion 14 presenting a convex arched edge 14' fitting 75 with the concave arched bottom 13' of cavity 13 in bar 10, and this bar 10 is pivotally united with the cross-bar 15 by means of a horizontal headed pin 16 which is secured in position by means of a forelock 80 17 passing through a hole thereof and which bears against a washer 18 mounted on the same pin 16.

On chassis 1 is supported by means of posts 19 a working platform 20 and on the 85 rear part thereof, the rear posts 19 properly enlarged and with other posts 21 hold a shade 22 for protecting the operator against the action of sunshine and rain.

The tread wheels 2 are operated from a 90 motor 23 supported on the fore part of the platform 20 by means of a transmission mechanism comprising a driving shaft 24 horizontally arranged in transverse position and gyroscopically mounted on journals 25 fixed 95 on platform 20, said driving shaft 24 presenting a crank 26 through which it connects with the connecting rod 27 articulated to the piston of an engine 23, and in said driving shaft are secured a fly-wheel 28 and 100 a gear wheel 29 meshing with another gear wheel 30 fixed on a transverse-horizontal shaft 31 gyroscopically mounted on bearing 32 secured beneath platform 20 and upon which is fixed at the side of gear wheel 30 105 33 connected by means of an endless chain 34 with another sprocket wheel 35 fixed to a long sleeve 36 loosely mounted on a third horizontal cross-shaft 37 gyroscopically mounted on bearings 38 se- 110

cured by means of screws beneath the sides of chassis 1, said sleeve having rigidly connected at its end one of the plates 39' of a clutch, the geared plate 39 of which forms part of the sleeve 40 wedged upon shaft 37 and sliding thereon and normally pushed against plate 39' by virtue of the elastic action of a helical spring 41 wound up on shaft 37 and bearing at one end against sleeve 40 and bearing at the other end against a collar 42 fixed upon shaft 37, and at each end of shaft out of chassis 1 is fixed a sprocket wheel 43 which is connected by means of an endless chain with a sprocket wheel 45 fixed on the rear shaft 3 between the chassis 1 and each driving wheel 2. The clutch of shaft 37 is operated by means of a hand lever 46 pivoted at its lower end on 47 upon a bracket 48 secured between two cross-bars 49 and 50 of chassis 1, and said lever is provided with a catching pawl 51 engaging with a gear segment 52 fixed on the two cross-bars 49 and 50, said lever 46 being pivotally connected at 53 with a link 54 articulated with the end of lever 55 connected at 56 with a fork embracing the sliding sleeve 40 of the clutch, said lever 55 being pivoted at 57 on the support 58 fixed to cross-bar 59 of frame 1.

30 Lever 46 is actuated by the operator from his seat 60 fixed on the middle of the rear part of platform 20, behind and above a box 61 such as a coach-box fixed beneath the platform 20 and inside of which the operator can place his legs.

35 The steering mechanism of the front wheels 5 consists of a double arm 62 horizontally arranged across the machine and securely mounted on a short vertical shaft 63 carrying at its upper end a beveled pinion 64 and which is gyratorily supported on a pending bracket 65 secured beneath a cross-bar 66 fixed at its bent ends to the sides of frame 1, and said double arm 62 presents at its ends lugs 67 downwardly directed and which gyratorily support horizontal projecting pins 68 carrying balls 69 provided with vertical trunnions 70 with which pivotally connect the forked ends of links 71, which at their other similarly forked ends pivotally connect with the inwardly extended upper portions of the supporting pieces 7 which hold the shafts 6 of front wheels 5. The beveled pinion 64 meshes with the beveled gear wheel 72 fixed at the end of a longitudinal horizontal shaft 73 gyratorily mounted on a bearing 74 secured beneath the cross-bar 59 of frame 1, said shaft 73 being connected by means of a 60 Cardan articulation 75 with a longitudinal inclined shaft 76 which passes above the platform 20 where it is supported on a bearing 77 formed in a bracket 78 projecting from the forward edge of the coach-box 61, and said shaft 76 bears at its free end a

fly-wheel 79 to be actuated by the operator from his seat 60.

Behind the rear part of frame 1 there are arranged a plurality of cutting edge disks 80 which are secured on a horizontal cross-shaft 81 gyratorily mounted on bearings 82 formed at the end of two longitudinal bars 83 pivotally connected at 84 on the end of two other longitudinal curved bars 85 mounted by their eye ends 86 on a pivoting shaft 87 horizontally mounted across the sides of frame 1, and said curved bars 85 are supported at their lowermost end on eyes 88 formed at the lower end of supporting arms 89 gyratorily mounted on shaft 80 3 of the tread wheels 2. The shaft 81 of disks 80 is suspended by its ends projecting toward the sides of the machine and by means of two links 90 and 91 articulated together from the ends of two supporting longitudinal inclined bars or beams 92 gyratorily mounted by means of bearings 93 secured beneath the same, on the shaft 3 of the tread wheels 2, between the latter and each sprocket wheel 45. Thus there is formed 90 between the two bars 83 and the two bars 92 a supporting frame for shaft 81 of disks 80 to enable them to be raised or lowered for adjusting its depth in the ground, to which effect it is only necessary to swing 95 the bars 92 upon shaft 3, and this is effected by means of a mechanism consisting in sleeves 94 through which are mounted the front ends of said bars 92 and which are horizontally pivoted on raised lugs 95 100 formed at the front outwardly bent ends of two levers 96 pivoted at 97 on the inner part of the sides of frame 1, these levers 96 being articulated at their other ends with curved links 98 which in turn are pivotally 105 connected at 98' with the ends of a horizontal A-shaped frame 99 which is longitudinally slidable along guides 100 and 101 fixed on cross-bars 49 and 50, and to one of the branches of the sliding frame 99 is rigidly 110 connected a standard 102 carrying at its upper end a fixed nut 103 which is slidably mounted on a worm-gear 104 arranged in horizontal longitudinal position and gyratorily supported on a rear standard 105 secured on cross-bar 50 and on a vertical supporting plate 106 transversely arranged and fixed at its ends on standards 107 fixed on the sides of frame 1 and in the front end of said worm-gear 104 is fixed a beveled 115 pinion 108 meshing with a beveled gear 109 the sleeve of which is loosely mounted on shaft 31 and has a plate 110 for engaging with the coupling 111 slidably mounted and coupled to shaft 37 and which is subjected 120 to the elastic action of the helical spring 112 wound up on said shaft 37 between the coupling 111 and bearing 32, said coupling 111 being operated by the lever 113 pivotally connected with a fork 113' embracing the 130

coupling, said lever 113 being pivoted at 114 beneath the platform 20 and to the free end of said lever 113 is pivotally connected an end of the curved link 115 which is articulated at its other end to the hand lever 116 pivoted at 117 on a supporting piece 118 fixed by means of screws to the inner face of a side of frame 1, the lever 116 being provided with a catching pawl 119 which 5 is engaged with a geared segment 120 formed at the top of said supporting piece 118. By properly actuating the hand lever 116, the coupling 111 is rendered operative or inoperative, thus clutching or unclutching the 10 same with the sleeve of the beveled gear 109, and compelling the shaft 31 to transmit its movement or not to transmit same to the worm-gear 104 for sliding the fixed nut 103 to the front or to the rear, as might be 15 the case, for lowering or raising the disks 80. In order to give the shaft 31 opposite gyratory movements, there is arranged between same and the driving shaft 24 a draw-back mechanism which is not illustrated because it is not considered necessary and 20 because same does not form a part of this invention.

With the object of guiding the curved links 98 in their sliding movement to the front or to the rear which is produced by 30 their connection with the branches of the sliding frame 99, there are provided on the shaft 37 peripherally channelled sleeves 121 on whose channel fit said links 98 on their lowered position, and with the same object 35 in view there are fixed to the inner face of the sides of the frame 1 triangular guiding pieces 122.

On shaft 81 of disks 80 are gyratorily 40 mounted by one eye on one of its ends a plurality of inverted V-shaped supporting pieces 123 held laterally to disks 80 by means of collars 124 fixed on shaft 81 and connected together at its center by a cross-horizontal 45 bar 125, and on the other end of said supporting pieces 123 are fixed a grate 126 and a mold board 127 each grate and mold-board reinforced together by plates 128 and each pair of mold-boards 127 are secured together 50 by means of curved plates 129 and besides at the side of said supporting pieces 123 there are secured cutting blades 130. On bar 125 are fixed two triangular plates 131 also connected together by another horizontal 55 bar 132 to which in turn are connected the mold-boards 127 by means of plates 133. In this manner a supporting frame is formed for the plows 126, 127, which frame is gyratorily on shaft 81 so as to raise or 60 lower at will the plows, independently from the disks 81, and this is obtained by means of a mechanism consisting of an inclined A-shaped frame 135 the two branches of which are mounted at their I-shaped ends 65 on pivots 136 projecting from the triangular

plates 131 and the other end of said frame 135 is pivotally connected to the side of a nut 137 slidably mounted on worm-gear 138 which is gyratorily supported at their ends on a standard 139 secured to the cross-bar 70 50 and on supporting plate 106, and said worm-gear 138 carries at its forward end a beveled pinion 140 meshing with a beveled gear 141 the sleeve of which is loosely mounted on shaft 131 and is provided with 75 a small plate 142 arranged for engaging with a coupling 143 which is coupled and slides on said shaft 31 and which is actuated by a crank-lever 144 pivotally connected with a fork 145 embracing the coupling, said lever 144 being pivoted on a support 146 secured beneath the platform 20, the other end of the lever 144 being connected by means of a curved link 148 with a hand lever 149 pivoted at 150 on a supporting piece 151 to the inner side of frame 1 and having at its top a geared segment 152 with which engages a catching pawl 153 slidably mounted on lever 149.

On the worm-gears 104 and 138 are arranged nuts 147 and 154 which serve as a butt for the sliding nuts 103 and 137 so as to limit their movement on said worm-gears.

There are also fixed beneath the cross-bar 59 of frame 1 square plates 155 projecting 95 downward and which serve as a butt to the double arm 62 of the steering mechanism in its backward turning movement, so as to prevent any excessive or undue deviation of the machine.

The operation of this machine is as follows: To move the machine, the hand lever 46 is actuated, once the catching pawl 51 has been disengaged from the geared segment 52, whereby the coupling 39 attains its coupling position so that shaft 37 may be actuated from the shafts 31 and 24, and the tread wheels 2 may be rotated by the intermediate of the sprocket wheels 43 and 45 and the endless chain 44. The disks 80 do the work 110 of cutting the ground thus aiding the work of the grates 126 which is that of lifting the ground already broken by the disks, at the same time that the blades 130 divide the lumps lifted by the grates 126 and the mold-boards stir up the lifted ground. The depth at which the disks 80 and the grates 126 are to work depends upon the class of the ground and the kind of labor which is to be performed thereon, and this depth is 115 graduated by raising or lowering to the desired point the supporting frame of disks 80, since the plows are mounted on a gyratory frame on the shaft 81 of the disks, and to effect this, once the catch 119 has been disengaged from the geared segment 120, the hand-lever 116 is properly actuated, whereby the coupling 111 attains its clutching position and the beveled gear 109 is rotated with shaft 31 and through the intermediate 120 125 130

of the beveled pinion 108 said beveled gear 109 causes the worm-gear 104 to be rotated, thereby producing the sliding movement of the nut 103 on said worm-gear and carrying along the sliding frame 99 which by means of the links 98 swings the levers 96 on their pivots 97 thus raising or lowering, as the direction of the movement may be, the forward ends of the supporting bars 92 which are swinging on shaft 3, whereby are respectively raised or lowered the rear ends of the same bars 92 which hold the shaft 81 of disks 80 together with the longitudinal bars 83 supported at 84. The same mode of operation is followed when there is found on the ground any obstruction that might injure the disks or plows, raising these working pieces by the proper action of the hand lever 116.

20 Whenever it is desired to raise the plows independently from the disks 80, for instance to cleanse off the earth gathered thereon or for replacing a grate, knife or mold-board, then the hand lever 149 is properly actuated, after disengaging the catch 155 from the geared segment 152, whereby the coupling 143 attains its clutching position and the beveled gear 141 is caused to turn with shaft 31 so that it may mesh with 25 the beveled pinion 140 and the worm-gear 138 be rotated, whereby the nut 137 slides on the latter and carries along with same the inclined frame 135 whose ends are connected to the triangular plates 131 that 30 move along the inverted V-shape supporting pieces 123 which rotate at their inner end on shaft 81 of disks 80 and assume the raised position shown by dotted lines on Fig. 1 of the drawings. Once the cleansing or repairing 35 operation of the plows has been completed, the same are lowered again actuating the general draw-back lever of shaft 31 and actuating in the manner already described the lever 149.

40 45 The supporting construction of the forward part of the machine on the front set of wheels, permits, when turning same in either direction for turning the machine that the latter may not incline itself, particularly on a sloping ground, owing to the fact that the arched support of the convex edge 14' on the concave bottom 13' of cavity 13 formed by the bar 10 that connects the two front wheels 2, permits the seat 13' 50 55 to rotate around the central pivot 16 and to slide itself on the edge 14' of the central portion 14 of cross-bar 15 fixed to frame 1, and to keep horizontal the latter.

It is obvious that the details of construction of the machine can be slightly changed without altering the features of the invention, which is as pointed out in the appended claims.

What we claim is:—

65 1. In plowing machines, the combination

of a plurality of cutting edge disks arranged behind the machine, a frame gyrorily mounted on the rear part of the machine and which rotatorily supports at its rear end the cutting edge disks, a second 70 frame hanging behind the first frame and pivotally mounted on the same, a plurality of plows secured on the second hanging frame and directly arranged behind each disk, lever actuated means for swinging 75 the first frame on its support so as to raise or lower the plows together with the disks for adjusting its depth into the ground and to allow its occasional raising, and lever actuated means for rotating the 80 hanging frame of the plows on the first frame so as to raise or lower the plows independently from the disks for the cleansing or repairing of the former.

2. In plowing machines, the combination 85 of a plurality of cutting edge disks arranged behind the machine, a frame which is gyrorily mounted on the shaft of the rear wheels of the machine and which supports at its rear end the disks of cutting edge, sliding means in the longitudinal direction of the machine for raising or lowering the front ends of said frame, a frame gyrorily mounted on the rear end of the disk supporting frame and behind the latter, a plurality of plows securely supported on this second frame, sliding means in the longitudinal direction of the machine for swinging this second frame on the first frame, and lever actuated means for independently operating the two sets of sliding means mentioned so as to raise or lower through one of said means the plows with the disks for adjusting the depth of their introduction into the ground and to allow 95 its occasional raising, and to raise or lower through the other means the plows independently from the disks for the cleansing or repairing of the former.

3. In plowing machines, the combination 110 of a plurality of cutting edge disks gyrorily mounted on a transverse shaft arranged behind the machine, a frame gyrorily mounted on the shaft of the rear wheels of the machine and which supports at 115 its rear end the shaft of the cutting disks, a gyratory worm-gear and sliding nut mechanism longitudinally arranged on the machine, a frame rigidly connected to the sliding nut and connected to the front end of 120 the supporting frame of the disks, lever actuated means for connecting or disconnecting the gyratory worm-gear from the driving shaft of the machine, a hanging frame behind the disks and gyrorily mounted on the shaft thereof, a plurality of plows secured on this hanging frame, a second 125 worm-gear and sliding nut mechanism longitudinally arranged on the machine, a frame connected to this sliding nut and to 130

the hanging frame that supports the plows, and lever actuated means for connecting or disconnecting this second gyratory worm-gear from the driving shaft of the machine, 5 so as to raise or lower, when actuating the first gyratory worm-gear, the plows together with the disks for adjusting its depth into the ground and to allow its occasional raising, and to raise or lower, when operating 10 the second operating worm-gear, the plows independently from the disks for the cleansing or repairing of the former.

4. In plowing machines, the combination of a plurality of cutting edge disks gyratorily mounted on a horizontal transverse shaft arranged behind the machine, two longitudinal bars or beams gyratorily mounted on the shaft of the rear wheels of the machine and which support at its rear end by 15 means of hanging links the shaft of the cutting edge disks, bars for connecting the shaft of the cutting edge disks with the bed of the machine, levers pivoted on longitudinal position at the rear part of the sides of 20 the machine bed and at whose front end are articulated the front ends of the supporting bars of the disk shaft, a gyratory worm gear and sliding nut mechanism longitudinally arranged on the machine, a frame rigidly 25 connected to the sliding nut, connecting 30 links between this frame and the rear ends of the lateral levers mentioned, lever actuated means for connecting or disconnecting 35 said gyratory worm-gear from the driving 40 shaft of the machine, a hanging frame behind the disks and gyratorily mounted on the shaft thereof, a plurality of plows secured on this hanging frame respectively behind the disks, a second worm-gear and sliding nut mechanism longitudinally arranged on the machine, a frame pivotally connected to this sliding nut and to the hanging frame that supports the plows, and

lever actuated means for connecting or disconnecting this second gyratory worm-screw 45 from the machine driving shaft, so as to raise or lower, when operating the first gyratory worm-gear, the plows together with the disks for adjusting its depth into the ground and to allow its occasional raising, 50 and to raise or lower, when operating the second gyratory worm - gear, the plows independently from the disks for the cleansing or repairing of the former.

5. In a plowing machine, a gyratory 55 earth working tool, a drag tool, a motor, a worm interconnectible with said motor operable to elevate said tools, a secondary worm interconnectible with said motor and operable to elevate said drag tool independ- 60

6. In a plowing machine, a gyratory earth working tool, a drag earth working tool, a motor, a shaft driven by said motor, a pair 65 of clutches on said shaft, and means whereby when one of said clutches is in engagement both said tools will be elevated by said motor and when the other said clutch is in engagement the said drag tool alone will be elevated.

7. In a plowing machine, an earth working tool, a worm and means whereby the said worm may be turned, a chassis, said worm extending longitudinal of said chassis and said tool behind said chassis, a nut 75 movable longitudinal of said worm by the rotation of said worm, a pivotal mount for said tool, and a rod interconnecting said nut and tool whereby said tool will be moved upon said pivotal mount by the rotation of 80 said worm.

In witness whereof we affix our signatures.

RAFAEL RAMOS.

AMBROSE DE CÁRDENAS.
